SAFETY RAZOR BLADE HOLDER

Jan de Swart, Los Angeles, Calif., assignor to
 Plastic Research Engineering Division of Vic-
 tory Manufacturing Co., South Pasadena, Calif.,
 a corporation of California

Application April 7, 1944, Serial No. 529,995

5 Claims. (Cl. 30—52)

This invention relates to a safety razor blade holder, and is intended, particularly, to provide a holder which is capable of being readily formed out of plastic material.

One of the objects of the present invention is to provide a novel form of release mechanism for a safety razor blade.

Another object of the present invention is to provide a novel, curved razor blade holder.

Another object of the present invention is to provide a form of razor which provides a curved fluted surface adapted to cooperate with a curved cutting blade and so shaped and arranged that an exterior guard for the cutting blade is not required, and to associate with the holder a novel means for holding the razor blade in position so as to dispense with the necessity of employing a guard for the blade.

Various further objects and advantages of the invention will be understood from the following description of the preferred form or example of the razor blade holder embodying the present invention. For that purpose I have hereinafter described a preferred example of my invention in connection with the accompanying drawing, in which

Figure 1 is a side elevation with the razor blade removed.

Figure 2 is an end elevation with the razor blade in position.

Figure 3 is an enlarged, fragmentary side elevation, mainly in vertical section.

Figure 4 is a top view of a razor blade for use in connection with the holder of the present invention.

Referring to the drawing, the razor blade holder comprises a body formed of plastic material which is provided with a handle 2 and a transversely extending blade-holding head 3. The blade-holding head 3 is provided with a curved and fluted face 4 for cooperating with the safety razor blade 5. The safety razor blade 5 is preferably curved longitudinally to closely conform to the curvature of the holes where the blade contacts the holder. The fluted surface of the holder permits the razor blade to fit closely against the holder, the flutes providing an opening for the hairs cut by the blades. By this form of the holder and blade it is possible with the razor of the present invention to dispense with the necessity of employing any guard for the blade.

The holder is provided with a fixed hook-shaped member 7 and a movable hook-shaped member 8, the two facing outwardly in opposite

directions. The hook-shaped members 7 and 8, in practice, pass through the rectangular opening 6 of the blade and secure the blade to the holder. The member 7 is integral with the head 3 of the body, while the hook 8 is attached to a plunger 10 which is reciprocably mounted in a longitudinal bore 11 in the head 3. The plunger 10 is yieldably urged into blade-holding position by a coil spring 12, positioned in the bore 11. A slightly elongated opening 9 is provided in the head 3 in order that the shank of the hook 8 may connect with the plunger 10 and a limited movement be provided for the plunger 10.

The holder is provided with an opening 13 in one of its ends and an operating button 14 connected to the plunger which extends through the opening. By means of the button 14 the two hooks 7 and 8 may be pressed together sufficient to release the blade 5.

For construction purposes, the end of the holder portion 13 may be provided with a cap 15 having a sliding fit with a reduced cylindrical flange 16 integral with the body of the device. After the spring and plunger have been assembled in the device, the cap 15 may be substantially integrally united with the remainder of the holder by the use of acetone, or similar solvent for plastic, for joining the cap 15 to the body.

While the particular form of the invention herein described is well adapted to carry out the objects of the invention, various modifications and changes may be made, and this invention is of the scope of the appended claims.

I claim:

- 35 1. A razor blade holder formed principally of plastic material, said holder comprising a body member having a blade-holding head and a handle extending transversely to the handle, said head having a stationary blade-holding hook and a movable blade-holding hook attached to a plunger movable in said bore, and spring means for yieldably urging said plunger outwardly.
- 40 2. A safety razor blade holder formed principally of plastic material and including a plastic body having a blade-holding head and a handle extending from the head, the head having a fluted and curved surface, a blade-holding hook protruding from the curved surface of said head, a movable blade-holding hook protruding from the surface of said head and attached to a plunger, a transverse bore in said head in which said plunger is movably mounted, and spring means yieldably urging said plunger into the expanded position.
- 45 3. A safety razor blade holder formed prin-

cipally of plastic material and including a plastic body having a blade-holding head and a handle extending from the head, the head having a fluted and curved surface, a blade-holding hook protruding from the curved surface of said head, a movable blade-holding hook protruding from the surface of said head and attached to a plunger, a transverse bore in said head in which said plunger is movably mounted, and spring means yieldably urging said plunger into the expanded position, the head having a separately formed cap for holding the plunger within the bore.

4. A safety razor blade holder comprising a body having a blade-holding head and a handle portion integrally formed of plastic material, the head having a separately formed cap member

permanently united to said head, a transverse bore through the head, a spring-actuated plunger movable in said bore and carrying a blade-holding hook, said head having a curved and fluted surface for contacting the razor blade.

5. A safety razor comprising a curved razor blade and a holder, said holder including a body member formed of plastic material and having a blade-holding head and a handle extending therefrom, the head being provided with a stationary blade-holding hook, a movable blade-holding hook attached to a plunger, and a transverse bore through said head in which said plunger is movably mounted, and a spring normally urging said plunger into the expanded position.

JAN DE SWART.
